CLAIM

The ornamental design for a grill cover assembly, as shown and described.

DESCRIPTION

FIG. 1 is a front perspective view of a new design for a grill cover assembly.

FIG. 2 is a front view of a new design for a grill cover assembly.

FIG. 3 is a rear view of a new design for a grill cover assembly.

FIG. 4 is a left side view of a new design for a grill cover assembly.

FIG. 5 is a right side view of a new design for a grill cover assembly.

FIG. 6 is a top view of a new design for a grill cover assembly.

FIG. 7 is a bottom view of a new design for a grill cover assembly.

FIG. 8 is a front perspective view of a new design for a grill cover assembly in use with an associated grill; and, FIG. 9 is a front perspective view of a new design for a grill cover assembly in use in a closed configuration.

The broken lines in the drawings depict portions of the grill cover assembly that form no part of the claimed subject matter. In FIG. 8, the additional broken lines depict environmental subject matter, specifically a grill and forms no part of the claimed design.

1 Claim, 9 Drawing Sheets
